TESTER FOR HEARING AID BATTERIES

Gaspare Bellafiore, 106 Eaton St.,
Providence, R.I. 02908

Filed Apr. 8, 1968, Ser. No. 11,363

Term of patent 14 years

Int. Cl. D10—10

U.S. Cl. D52—6

FIG. 1

FIG. 2

FIG. 3

FIG. 4

FIG. 5

FIG. 1 is a perspective view of a tester for hearing aid batteries showing my new design;

FIG. 2 is a side elevational view thereof;

FIG. 3 is a bottom plan view thereof;

FIG. 4 is a top plan view thereof; and

FIG. 5 is a vertical section taken along lines 5—5 in FIG. 1.

I claim:

The ornamental design for a tester for hearing aid batteries, substantially as shown.
